UNITED STATES PATENT OFFICE.

TOBIAS L. CRANE, OF MORENCI, ARIZONA.

ORE-CONCENTRATOR.

1,116,246.

Specification of Letters Patent.

Patented Nov. 3, 1914.

Application filed February 4, 1914. Serial No. 816,511.

To all whom it may concern:

Be it known that I, TOBIAS L. CRANE, a citizen of the United States, residing at Morenci, in the county of Greenlee and 5 State of Arizona, have invented certain new and useful Improvements in Ore-Concentrators; and I do hereby declare the following to be a full, clear, and exact description of the invention, such as will enable others 10 skilled in the art to which it appertains to make and use the same.

One of the objects of this invention is to provide an improved deck for ore concentrators having the riffles so designed and arranged as to secure the maximum efficiency 15 and capacity.

Another object of the invention is to provide an ore concentrator having a feed box of V-shaped cross section and extending parallel 20 to the rear of the deck adjacent the edge thereof, having the front of the deck so constructed as to permit the concentrates to discharge along the entire length thereof, and having the run for the dressing water 25 extended the full length of the front of the table and part way along the head thereof.

With these and other objects in view as will become more apparent as the description proceeds, the invention consists in certain 30 novel features of construction, combination and arrangement of parts as will be hereinafter more fully described and claimed.

For a complete understanding of my invention, reference is to be had to the following description and accompanying drawings, in which—

Figure 1 is a top plan view of my improved ore concentrator deck, and Fig. 2 is a 40 section taken on the plane of line 2—2 of Fig. 1.

Referring in detail to the drawings by numerals, 5 designates, generally, a deck which is more specifically designated by the 45 corner numerals 6, 7, 8, 9 and 10. For the sake of clearness and brevity in the following description, the side 6—7 will be designated the head of the table; 7, 8, 9 the rear of the table, 9—10 the foot; and 6—10 the 50 front. A wall 11 projects above the deck at the head and rear of the table and troughs 12 and 13 are provided at the front and foot of the deck respectively to receive the concentrates and the tailings. The trough 12 55 extends the full length of the front and is arranged to receive the concentrates as

they drop from the deck. This trough is separated from the trough 13 by a partition 14 and is provided adjacent one end with a discharge opening 15. The trough 13 extends the full length of the foot of the deck to receive the tailings as they drop therefrom and is provided with a discharge opening or port 16. These troughs, it will be understood, may be made of any desired construction, and for the purpose of illustration I have shown them as being formed by an inner wall 17 extending downwardly from the edge of the table, a bottom wall 18 and an outer wall 19.

In carrying out my invention, I cover that portion of the deck defined by the numerals 7, 8, 20, 21 and 22 with a plurality of slightly curved riffles 23 and 24. The riffles 23 extend from the rear to the front of the 75 deck and have a general direction parallel to the head. It will be noted, however, that the rear portions of these riffles are curved slightly toward the head of the table and that the degree of curvature increases gradually in relation to the nearness of the riffle to the head of the table. The riffles 24 extend from the front of the deck rearwardly and terminate in engagement with the head wall.

That portion of the deck defined by the numerals 20, 16, 25 and 21 is provided with a series of straight riffles 26 which extend from the front of the deck toward the rear at a slight inclination to the head of the 90 table. These riffles terminate short of the rear wall of the table and their rear ends are arranged in a plane extending substantially parallel to the rear edge 8—9 of the deck.

A feed box 27, V-shaped in cross section, is arranged adjacent the rear edge of the table and extends parallel to the rear wall defined by the numerals 7—8. The feed box extends from the head wall to a point 100 about centrally of the wall 7—8. A run or trough for the dressing water is supported over the deck by suitable arms 28 and extends along the full length of the front side of the deck and about half the length 105 of the head.

In operation the pulps or slimes are placed in the feed box and from there are discharged onto the deck, and as the deck is agitated, the concentrates feed forwardly 110 into the trough 12 and the tailings are carried into the trough 13. Any suitable

means, not shown, may be provided for properly agitating the table and adjusting the inclination thereof to secure a proper operation of the concentrator.

5 From the foregoing description taken in connection with the accompanying drawings, it will be apparent that I have provided a very efficient concentrator having novelly arranged riffles and a new arrangement of feed box and dressing water run, as 10 well as a concentrate discharge portion of the maximum length.

While I have shown and described the preferred embodiment of my invention, it 15 will be understood that minor changes in construction, combination and arrangement of parts may be made without departing from the spirit and scope of the invention as claimed.

20 Having thus described my invention, I claim:—

In an ore concentrating table, a retaining wall extending along the head and rear thereof, a concentrate trough running along 25 the front of the table, a tailings trough extending along the foot of the table, a series of riffles running from the rear to the front

of the table and curving adjacent their rear ends toward the head of the table, a second series of riffles arranged between said 30 first mentioned series and the head of the table, and extending from the front of the table in gradual curves into engagement with the head thereof, a third series of riffles located adjacent the foot of the table and 35 running from the front edge thereof toward the rear of the table at a slight inclination to the head, said last mentioned riffles terminating in spaced relation to the rear wall, a feed box arranged at the rear of the table 40 adjacent the head thereof and extending across a number of the riffles forming the first mentioned series and a run for the dressing water, said run being supported above the surface of the table and extending 45 the full length of the front edge thereof and part way along the head of the table.

In testimony whereof I affix my signature in presence of two witnesses.

TOBIAS L. CRANE.
